UNITED STATES PATENT OFFICE.

ENOCH GEORGE, JR., OF PITTSBURGH, PENNSYLVANIA, ASSIGNOR TO THE McCONWAY & TORLEY COMPANY, A CORPORATION OF PENNSYLVANIA.

DRAFT YOKE.

Application filed January 19, 1926. Serial No. 82,300.

My invention relates to draft yokes employed in draft rigging for railway cars. The principal object of the invention is to afford a draft yoke of simple and easily manufactured form which efficiently lends itself to the application thereto of a rugged and readily replaceable wearing shoe for relieving the yoke of the wear incident to its movement with respect to the strap or carrier by which it is supported in service. It is also the object of the invention to provide a construction which not only efficiently and reliably performs its principal functions but which minimizes likelihood of breakage of the wearing shoe or the displacement and loss of the parts of a shoe should the latter break while in service. A still further object of the invention is to produce a strong and reliable design of yoke which distinctly suggests the necessity of applying a wearing shoe thereto, thus reasonably insuring against the shoe being omitted by the car builder or car repairman. Another object of the invention is to provide a form of yoke which is well adapted for being made of cast steel and which may be finished with the expenditure of little labor for cleaning the casting. A still further object of the invention is to provide a simple form of wearing shoe which may in an emergency be easily made from a rectangular piece of metal.

A primary feature of the invention consists in providing one of the arms of the draft yoke with a plurality of outwardly projecting lugs which are spaced from each other longitudinally of the yoke and are adapted to engage a wearing shoe for cooperating with the yoke support, the said lugs serving as means for restraining longitudinal and lateral shifting of the wearing shoe with respect to the yoke.

A further feature of the invention consists in providing one of the arms of the draft yoke with a plurality of outwardly projecting lugs arranged in pairs, the lugs of each pair being spaced laterally of the yoke arm and the lugs of adjacent pairs being spaced longitudinally, and in combining therewith a wearing shoe formed with portions which intervene between adjacent faces of neighboring lugs when the parts are in assembled relation.

Other features of the invention consist-

ing in advantageous details of construction and arrangement of parts will hereinafter appear and be pointed out in the claims.

In the drawings illustrating the invention

Figure 1 is a side elevational view of a draft yoke and wearing shoe embodying the invention.

Figure 2 is an inverted plan view of the construction shown in Figure 1.

Figure 3 is a view in elevation of the forward end of the yoke shown in Figures 1 and 2.

Figures 4 and 5 are a plan view and side elevation respectively, of the wearing shoe illustrated in Figures 1 and 2.

Figures 6 and 7 are a plan view and side elevation respectively, of a slightly modified form of wearing shoe suitable for use with the yoke illustrated in Figure 1.

Figures 8 and 9 are a plan view and side elevation respectively, of another modified form of wearing shoe adapted to be used with the yoke shown in Figure 1.

Figure 10 is a view partly in side elevation and partly in vertical section of a modified form of draft yoke and cooperating wearing shoe embodying the invention.

Figure 11 is an inverted plan view of the construction shown in Figure 10.

Figure 12 is a view partly in end elevation and partly in vertical section of the modified form of yoke shown in Figures 10 and 11.

Figures 13 and 14 are respectively a plan view and a side elevational view of the form of wearing shoe illustrated in Figures 10 and 11.

Figures 15 and 16 are detail views corresponding to Figures 13 and 14 respectively.

Figures 17 and 18 are respectively a plan view and a side elevational view of a modified form of wearing shoe suitable for use with the yoke shown in Figure 10.

The form of yoke illustrated in the drawings for the purpose of explaining the invention is of the quadruple shear type, its forward end being fashioned with an upper lug 1, a lower lug 2 and an intermediate lug 3, each of which is perforated to receive a pivot pin or tail pin for connecting a car coupler thereto.

The upper and lower arms, 4 and 5 respectively, of the draft yoke are spaced apart to receive a cushioning device (not

shown) between them, the rear ends of said arms being rigidly connected by a transversely extending portion 6 which, as shown, is preferably of I-beam cross section and may be advantageously flanged intermediate, as indicated at 7.

Intermediate its ends the lower arm 5 of the yoke is integrally formed with a plurality of downwardly projecting lugs 8 which are preferably of generally rectangular cross section and somewhat tapered. These lugs are arranged in pairs, being spaced from each other laterally of the yoke arm. A plurality of pairs of lugs 8 are employed, the corresponding lugs of adjacent pairs being spaced from each other in the direction of length of the yoke. By this means spaces or recesses are provided between the lugs for receiving intervening portions of the wearing shoe 9 and the latter may be assembled with the yoke in several different locations, thus suiting its position to practically any location of yoke support or carrier with which the railway car may be provided and at the same time affording it adequate bearing surface.

The lower face of the wearing shoe 9 is slidably supported by a draft gear carrier iron 10 which has been diagrammatically illustrated by dotted lines in Figure 1. The shoe for cooperating with the draft yoke illustrated in Figures 1, 2 and 3 is preferably of cruciform configuration so as to provide adjacent angularly disposed faces or shoulders 11 and 12 respectively for engaging the corresponding lugs 8 of the yoke and so as also to provide projecting arms or portions 13 and 14 adapted to intervene between the adjacent faces of neighboring lugs 8. By this means the outwardly projecting lugs upon the yoke cooperate with the wearing shoe 9 so as to prevent both longitudinal and lateral shifting of the shoe with respect to the yoke. The shoulders 11 and 12 of the wearing shoe are preferably beveled in correspondence with the tapering lugs 8; and, as shown in Figures 4 and 5, the shoe 9 when made as a casting or forging may advantageously be recessed on its upper side in order to minimize waste of metal. The wearing shoe 15 illustrated in Figures 6 and 7 is substantially the same as that shown in Figures 4 and 5 except that its upper side is not recessed and accordingly similar details of construction have been indicated by corresponding reference numerals. The wearing shoe 16 illustrated in Figures 8 and 9 is of general H-form being provided intermediate its ends with oppositely disposed recesses 17 each of which is adapted to receive one of the lugs 8 of the yoke. When the parts are in assembled relation the walls or shoulders 18 of each of these recesses is adapted to engage the opposite sides of a cooperating lug 8 while the

intermediate portion 19 of the shoe intervenes between transversely spaced lugs 8 and the end portions 20 of said shoe are disposed between adjacent longitudinally spaced lugs.

In the modified form of the invention illustrated in Figures 10, 11 and 12 the lower arm of the yoke is integrally fashioned with a series of downwardly projecting lugs 21 which are spaced from each other longitudinally of the yoke and preferably are of conical form. The remaining structural features of this form of yoke are the same as those heretofore described and accordingly similar parts have been identified by corresponding reference numerals. The lugs 21 cooperate with a wearing shoe 22 having correspondingly tapered openings or recesses 23 for receiving the lugs 21. As will be readily perceived the wearing shoe may be caused to cooperate with the lugs so as to occupy any one of three different positions, thus suiting its location to that of the particular support with which the car may be equipped.

The modified form of shoe 24 shown in Figures 15 and 16, is identically the same as that illustrated in Figures 10, 11, 13 and 14 except that the recesses 25 for receiving the lugs 21 do not extend entirely through the shoe. The wearing shoe 26 shown in Figures 17 and 18, instead of having lug receiving openings intermediate its ends, is provided with oppositely disposed open sided recesses 27 for receiving adjacent lugs 21 of the yoke.

It will be perceived that my invention provides a wearing shoe having long life in service and which is not liable to crack, drop out and be lost. It will also be perceived that the cooperating parts are of such form that casting defects are not apt to be produced in the yoke and that the wearing shoes may be readily made in case of an emergency.

I claim:

1. A draft yoke closed at its rear end and formed at its forward end for connection with a car coupler, said yoke being provided with spaced arms adapted to receive a cushioning device between them, in combination with a wearing shoe for cooperating with a yoke support, one of the arms being provided with a plurality of outwardly projecting lugs spaced from each other longitudinally of the yoke and adapted to cooperate with said wearing shoe to prevent longitudinal and lateral shifting of the latter.

2. A draft yoke closed at its rear end and formed at its forward end for connection with a car coupler, said yoke being provided with spaced arms adapted to receive a cushioning device between them, in combination with a wearing shoe for cooperating with a yoke support, one of said arms being pro-

vided with a plurality of pairs of outwardly projecting lugs, the lugs of each pair being spaced laterally of the yoke arm and the lugs of adjacent pairs being spaced longitudinally of the yoke arm, and said wearing shoe being provided with portions intervening between adjacent faces of neighboring lugs.

- 5 3. A draft yoke closed at its rear end and formed at its forward end for connection with a car coupler, said yoke being provided with spaced arms adapted to receive a cushioning device between them, in combination with a wearing shoe for cooperating with a yoke support, one of said arms being provided with a plurality of spaced vertically tapered outwardly projecting lugs, and said wearing shoe being provided with recesses having tapered walls for engaging said lugs.
- 10 4. A draft yoke closed at its rear end and formed at its forward end for connection with a car coupler, said yoke being provided with spaced arms adapted to receive a cushioning device between them, in combination with a wearing shoe for cooperating with a yoke support, one of said arms being provided with a plurality of outwardly projecting lugs spaced to provide a continuous bearing surface for the shoe extending on
- 15 opposite sides of the longitudinal axis of the yoke, and the wearing shoe having a portion projecting into the space between adja-

cent faces of said lugs and engaging said bearing surface.

5 5. A draft yoke closed at its rear end and formed at its forward end for connection with a car coupler, said yoke being provided with spaced arms adapted to receive a cushioning device between them, one of said arms being provided with a plurality of pairs of outwardly projecting lugs, the lugs of each pair being spaced laterally of the yoke arm to provide an intervening bearing surface for cooperating with a portion of a wearing shoe.

10 6. A draft yoke closed at its rear end and formed at its forward end for connection with a car coupler, said yoke being provided with spaced arms adapted to receive a cushioning device between them, one of said arms having a plurality of projections spaced to provide an uninterrupted and continuous bearing surface extending transversely of the yoke arm across the longitudinal axis of the latter to engage a portion of a wearing shoe.

15 7. A wear shoe of cruciform configuration, the adjacent angularly disposed walls thereof being adapted to receive downwardly projecting lugs formed on the lower arm of a draft yoke.

20 In testimony whereof I affix my signature.

ENOCH GEORGE, Jr.
